UNITED STATES PATENT OFFICE.

GUY L. BONHAM, OF WEST HARTFORD, CONNECTICUT.

CAR-MOVER.

1,343,430.

Specification of Letters Patent. Patented June 15, 1920.

Application filed October 20, 1919. Serial No. 331,836.

To all whom it may concern:

Be it known that I, GUY L. BONHAM, a citizen of the United States, residing at West Hartford, in the county of Hartford and State of Connecticut, have invented a new and useful Car-Mover, of which the following is a specification.

This invention relates to improvements in car movers and is designed more especially as an improvement upon the structure disclosed in my Patent 1,315,905, dated Sept. 9, 1919.

One of the objects of the invention is to provide a device of this character in which the stem of the gripping head is caused to move forwardly and upwardly during the operation of the device, thus to cause said head to travel upwardly and forwardly with the gripped portion of the wheel and prevent tilting of the mover.

Another object is to provide means whereby the gripping jaws are automatically released from the car wheel during their downward movement, thereby to allow the head to be reciprocated and impart successive rotations to the wheel.

A still further object is to provide a novel changeable fulcrum for the operating lever.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings

Figure 1 is a central vertical section through the device.

Fig. 2 is a front elevation, parts being broken away and shown in section and one side of the standard or pedestal being detached.

Fig. 3 is a plan view of the gripping head.

Fig. 4 is a plan view of the pedestal.

Fig. 5 is a view partly in section and

partly in elevation of one of the gripping jaws and adjacent parts.

Fig. 6 is a perspective view of a jaw.

Referring to the figures by characters of reference, 1 designates a hollow pedestal which may, if desired, be provided with one side 2 formed of a separate piece, although the entire pedestal can be formed in one piece. This pedestal is mounted on a base 3 swiveled thereon as at 4 and anti-friction bearings 5 are interposed between the base 6 and pedestal. The base is adapted to rest on a rail R and has depending corner lugs 6 for engaging the sides of the head of the rail.

The pedestal has an arcuate portion 7 extending forwardly therefrom and provided with an elongated opening or slot 8 from opposite walls of which project opposed studs 9. Ribs or projections 10 and 11 extend from the pedestal below the opening 8 and are overhung by the housed arm 12 of an actuating lever 13 in which is formed a socket 14 for the reception of a handle not shown. Spaced notches 15 are formed in the arm 12 of the lever and are adapted successively to receive the respective projections 10 and 11 when the lever is swung relative to the pedestal, there being grooves 16 in the sides of the lever for the reception of the studs 9. Thus it will be seen that when the lever 13 is inclined with its socket end raised, the projection 11 rests in one recess 15 and constitutes the fulcrum of the lever and as the lever is pressed downwardly at its outer end the next recess 15 receives the projection 10 and finally the studs 9 are received within the grooves 16.

The arm 12 of the lever has an upwardly projecting ear 17 pivotally engaged by one end of a short curved plunger 18 which, in turn, is pivotally connected to the lower end of an arcuate stem 19 slidably mounted in a curved passage 20 in the upper portion of the pedestal 1. A head 21 is swiveled on the upper end of this stem, as at 22 and has its side portions curved to form arms 23 embracing the car wheel W to which it is to be applied. End recesses 24 are formed in the arms and are provided with end closure plates 25 and seated in these recesses are the rounded inner ends of cam shaped gripping jaws 26 having tapered bosses 27 bearing in recesses 28 provided therefor. Rods 29 are

secured to the jaws and are journaled in the respective arms and these rods have terminal arms 30 depending therefrom and overhanging a deflecting cap 31 on the top of the pedestal. Springs 32 are arranged to hold the upper ends of the jaws normally pressed inwardly and the lower ends of the arms 30 normally in position over the cap 31.

In using the device the base 3 is placed on rail R close to the wheel W to be moved and the jaws 26 are positioned at opposite sides of the wheel. As the head 21 approaches its lowermost position the arms 30 are brought against the top of cap 31 so as to cause the jaws to swing apart ready to re-engage the wheel W. By thrusting down on the outer end of the lever 13 the inner arm of the lever will move the plunger 18 and the stem 19 upwardly along a curved line. As soon as the head 21 begins to move upwardly the arms 30 will lift off of the cap 31 and the jaws 26 will grip the sides of the wheel W under the action of the springs 32. Thus the wheel will be rotated, the curved stem 19 causing the head and jaws to follow the moving gripped portion of the wheel without displacing the pedestal by tilting or sliding it. By then reversing the movement of the lever the head 21 will move downwardly, the frictional engagement of the jaws with the sides of the wheel causing the jaws to swing outwardly and become disengaged from the wheel until the jaws are brought to their lowermost positions whereupon the arms 30 will engage the cap 31 and cause the jaws to open wide preparatory for the next engagement with the sides of the wheel, thereby restraining the action of the springs 32 until ready for the next engagement with the sides of the wheel.

What is claimed is:—

1. In a car mover the combination with a pedestal, of a wheel gripping head, a curved stem depending therefrom, and means for

actuating the stem along a curved line to move the head upwardly and forwardly with that portion of a wheel gripped by the head. 45

2. In a car mover the combination with a pedestal, of a head, wheel gripping means carried thereby, an actuating lever, and means in the pedestal and operated by the lever for moving the head upwardly and forward on a curved line with the gripped portion of the wheel and relative to the pedestal. 50

3. In a car mover the combination with a pedestal, of a head, gripping means thereon, an arcuate stem depending from the head, and slideable along a curved line within the pedestal, and means supported by the pedestal for actuating the stem. 55

4. In a car mover the combination with a pedestal, of a head, opposed gripping jaws carried thereby, depending arms movable with the respective jaws, and means for lowering the head to direct the arms against the pedestal for automatically opening the jaws preparatory for the next engagement with opposed faces of a wheel. 60

5. In a car mover the combination with a pedestal, of an arcuate stem slideable thereon along a curved line, a head on the stem, opposed gripping jaws on the head, arms movable with the respective jaws, an arresting cap for holding the arms from moving below a predetermined point while the head continues its downward course to open the jaws from engagement with a wheel therebetween, a lever projecting into the pedestal, and a plunger connection between the lever and stem. 70

In testimony that I claim the foregoing as my own, I have hereto affixed my signature in the presence of two witnesses.

GUY L. BONHAM.
